[57] CLAIM

The ornamental design for a combined mop and wringer, as shown and described.

DESCRIPTION

FIG. 1 is a front elevational view of a combined mop and wringer showing our new design, shown with the mop head completely withdrawn in the wringer portion;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is a perspective view thereof, shown with the mop head completely extended;

FIG. 9 is a perspective view thereof, shown with the mop head partially extended; and

FIG. 10 is an enlarged bottom perspective view of the mop of FIG. 1.

The combined mop and wringer is partially shown in FIGS. 8-10 for ease and clarity of illustration.
